Hubbard & Smith,
Shaft Hanger,
No 80,546, Patented Aug. 4, 1868.

United States Patent Office.

GEORGE W. HUBBARD AND SCOTT A. SMITH, OF PHILADELPHIA, PENNSYLVANIA

Assignors to Cresson & Smith, of the same place.

Letters Patent No. 80,546, dated August 4, 1868.

IMPROVEMENT IN HANGERS FOR SHAFTING.

The Schedule referred to in these Letters Patent and making part of the same.

TO ALL WHOM IT MAY CONCERN:

Be it known that we, GEORGE W. HUBBARD and SCOTT A. SMITH, both of the city and county of Philadelphia, in the State of Pennsylvania, have invented new and useful Improvements in Hangers for Shafting; and we do hereby declare that the following is a full, clear, and exact description thereof, which will enable others skilled in the art to make and use the same, reference being had to the accompanying drawing, forming part of this specification, in which—

Figure 1 is an elevation of the hanger A.

Figure 2 is a vertical section through $x x$.

Figure 3 is a horizontal section through the line $y y$.

The general construction of this hanger is what is known as the ball-and-socket pattern, that is, the boxes c and d are held in position by two concave-ended adjusting-screws a' a' , in contact with corresponding convex surfaces on the top side of the upper box c , and the bottom side of the lower box d . These screws a' a' have square openings a'' a'' in their centre, into which may be introduced the square end of a wrench, for the purpose of screwing them up or down, in adjusting the boxes c d , and firmly holding the same.

The set-screws b' b' keep the adjusting-screws a' a' from being displaced, after having been properly adjusted.

The above-described peculiarities of this hanger are old and well known, and to them we lay no claim.

The first part of our invention consists in so constructing this hanger A that one pattern may be used for several sizes of shaft, while at the same time the material is put into such form that it acts to the best advantage in securing strength and stiffness. This result is accomplished by making the body of the hanger hollow, (as shown by the dotted lines at b'' in fig. 1, and at b'' in fig. 3,) and by using cores of different sizes in the space b'' , in combination with a space at B large enough to receive between the ends of the adjusting-screws a' a' , the several sizes of boxes.

In practice, we find that three sizes of shafts for each hanger-pattern is the number which can be used to the best advantage, as, for instance, a two-inch, two-and-a-quarter-inch, and two-and-a-half-inch bore of box.

The new results obtained by this improvement may be stated as follow: first, a simple pattern may be used for several sizes of shafts; second, a very stiff hanger is made with a minimum of metal; third, a very strong hanger can be made for special uses, as, for instance, the hangers in a main line of shafting, which take the strain from an engine, by much reducing the size of the core b'' .

The second part of this invention consists in a method of adapting a self-oiling apparatus to ball-and-socket hangers, whether made with or without the above-mentioned improvement.

In combining a self-oiling apparatus with a ball-and-socket hanger, our object is to provide means for bringing the reservoir of oil close to the lower side of the shaft, and at the same time in the centre of the bearing, as we believe this to be the point at which oil should be applied, particularly in a ball-and-socket-hanger, in which the centre of the bottom box is the point at which it would first heat, in the absence of oil, because it there rests upon the adjusting-screw a' . It is also quite requisite to the successful working of a self-oiling apparatus, that some means should be provided for readily removing the same for examination. These requirements are met, and this part of our invention consists solely in utilizing the space in the centre of the bottom adjusting-screw a' , for conducting oil, by capillary attraction, or other equivalent means, to the bottom of the shaft, in combination with an opening in the bottom box, and a means for returning the oil to a reservoir, to be again raised to the shaft. One mode of utilizing the space in the centre of the adjusting-screw a' , is by enlarging the opening a'' , and forming a reservoir at c'' , in combination with the circular opening o , in the centre of the bottom box. Into this reservoir c'' is introduced a piece of wood, L, covered with the wick l' , all enclosed in the cylinder of tin l'' . The tin cylinder, wick, and wood are fastened together by nails at n' . A spiral spring, N, forces the wick up against the shaft. The oil is drawn up through the wick by capillary attraction, and flows out on the shaft as far as the recesses $c' c'$, in the ends of the boxes, and is returned again to the reser-

voir by means of a channel, d'' , cut in the bottom of the box d . Openings are provided at d'' , into which oil may be poured at any time, to fill up the reservoir c'' .

To remove the reservoir c'' for examination, it is only necessary to prop up the shaft and unscrew the reservoir a' , first marking it to its place.

What we claim as our invention, and desire to secure by Letters Patent, is—

1. The cored spaces b' , in combination with the enlarged opening B , in a ball-and-socket hanger, when made for the purpose specified.

2. The combination of the oil-reservoir c'' , in the lower adjusting-screw a' , with the opening o and the channel d' in a ball-and-socket hanger, all constructed substantially as described, and for the purpose specified.

GEO. W. HUBBARD,
SCOTT A. SMITH.
